[57] CLAIM

The ornamental design for a work station upper body support, as shown and described.

DESCRIPTION

FIG. 1 is a top plan view of the work station upper body support showing my new design;
FIG. 2 is a bottom plan view of the support;
FIG. 3 is a front elevational view of the support;
FIG. 4 is a rear elevational view of the support;
FIG. 5 is a left side elevational view of the support;
FIG. 6 is a right side elevational view of the support;
FIG. 7 is a left side elevational view of the support shown with the left half removed to reveal features of the support not visible in FIGS. 1-6.
FIG. 8 is a top perspective view; and,
FIG. 9 is a bottom perspective view thereof.
